UNITED STATES PATENT OFFICE.

HENRY W. EASTHAM, OF BEVERLY, MASSACHUSETTS, ASSIGNOR TO UNITED SHOE MACHINERY COMPANY, OF PATERSON, NEW JERSEY, A CORPORATION OF NEW JERSEY.

SOLE-PRESSING MACHINE.

1,117,557.

Specification of Letters Patent. Patented Nov. 17, 1914.

Application filed April 2, 1913. Serial No. 758,329.

To all whom it may concern:

Be it known that I, HENRY W. EASTHAM, residing at Beverly, in the county of Essex and State of Massachusetts, have invented 5 certain new and useful Improvements in Sole-Pressing Machine; and I do hereby declare the following to be a full, clear, and exact description of the invention, such as will enable others skilled in the art to which 10 it appertains to make and use the same.

The present invention relates to sole pressing machines and more particularly to machines of that class known as sole molding machines which are employed for shaping 15 a sole before it is incorporated in the boot or shoe.

The object of the present invention is to provide certain improvements in a machine of this type for accurately positioning a 20 sole preliminary to the pressing operation without necessitating any changes in the construction or mode of operation of the co-operating pressing forms.

With this object in view, one feature of 25 the invention consists in the provision of a gage permanently located in a sole engaging position with relation to the supporting form and having a sole engaging edge normally projecting above the upper 30 surface of the sole. In the simplest and most efficient form of the invention which has yet been devised the gage member is formed of resilient material and is provided with a curved sole engaging edge projecting 35 above the upper surface of the sole and arranged to flatten out when the co-operating forms are moved into pressing position while maintaining a constant lateral position with relation to the forms.

Still further features of the invention consist in certain novel features of construction, combinations and arrangements of parts hereinafter described and claimed, the advantages of which will be obvious to those 45 skilled in the art from the following description.

In the accompanying drawings: Figure 1 is a vertical longitudinal section of a portion of a well-known type of sole molding machine 50 embodying the present invention in its preferred form; Fig. 2 is a detail plan view partly broken away, of the lower form carrying slide and associated gages and gripping device; Fig. 3 is a detail illustrating

a side elevation partly in section, of the 55 construction shown in Fig. 2; and Fig. 4 is a detail illustrating the side gage when the two co-operating forms are in pressing position.

The machine shown in the illustrated embodiment of the invention consists of an upper form 1 removably secured in the usual manner on a carrier 2 which is supported by a stationary cross head 3 and is vertically adjustable by means of a wedge 60 4. The lower form is indicated at 5 and is removably mounted upon a slide 6 which reciprocates in horizontal guideways formed in a vertical reciprocating cross-head 7. Reciprocatory movements are imparted to the 65 cross-head 7 from a crank shaft 8 by means of a link 9 and toggle levers 10. Reciprocating movements are imparted to the slide 6 transversely to the reciprocating movements of the cross-head 7 by means of a 70 bell crank 11 which is mounted upon the cross-head 7 and has one arm connected to the slide 6 by means of a link 12, the other arm of the bell crank being connected by a link 13 to an arm 14 integral with a rock 75 shaft 15 journaled upon the frame of the machine. An arm 16 extends rearwardly from the rock shaft 15 and is connected by a tension spring 17 to the stationary cross-head 3. During the rising and falling movements of the cross-head 7 the bell crank 11 is rocked and imparts inward and outward movements to the slide 6.

The heel end of the sole is positioned longitudinally of the lower form by a gage 80 20 adjustably mounted upon the form carrying slide in the usual manner and contacting with the heel end of the sole throughout the entire pressing operation. During the horizontal movement of the 85 form carrying slide into pressing position a gripping device 21 pivotally supported upon the form carrying slide is actuated in the usual manner to clamp the heel end of the sole through a stationary roll 22 engaging 90 100 with the upper face of the gripping arm. In order to allow the gage and gripping devices to remain in contact with the sole during the pressing operation the heel end of the pressing form is provided with a cut-away portion, as indicated clearly in Fig. 1.

The above described construction forms no part of the present invention and has

been only briefly described as it is substantially the same as that disclosed in the U. S. patent to Preble, No. 1,004,075, dated September 26, 1911.

5 In addition to gaging the position of the sole longitudinally, it is desirable to provide a simple and compact mechanism for accurately determining the relative lateral position of the sole and form. It is furthermore 10 desirable that the gage member shall contact with and position the sole during the entire pressing operation, and that the employment of the gage member shall not necessitate any alterations in the construction 15 or mode of operation of the forms. To this end the gage member is permanently located in a sole engaging position with relation to the supporting form and is arranged to yield upon a movement of the forms into 20 pressing position while maintaining a constant lateral position of the sole engaging edge.

The machine shown in the illustrated embodiment of the invention is provided with 25 a resilient arch shaped gage member 25 having its opposite ends resting upon the supporting form and arranged to yield as the supporting form moves into a pressing position until it occupies the space between the 30 two forms equaling the thickness of the sole under pressure, as shown clearly in Fig. 4. The sole engaging edge of the member is curved in conformity with the curvature of the sole edge, and as the gage flattens out 35 under pressure, the relative lateral position of the sole engaging edge and the forms remains constant. With this construction the edge of the gage member remains in contact with the sole edge throughout substantially 40 the entire thickness of the edge during the pressing operation. The gage is conveniently supported upon the free end of an arm 27 pivotally mounted at 28 on a bracket 29 secured to the form carrying slide 6. The 45 gage is adjusted laterally by swinging the arm 27 about its pivotal connection and is locked in any adjusted position by a stud 31 formed upon the arm which engages with one of a plurality of recesses 30 formed in 50 the face of the bracket. The arm 27 is conveniently manipulated by a handle 32 formed upon the end of the arm.

While it is preferred to employ the specific construction and arrangement of parts 55 shown and described, it will be understood that this construction and arrangement is

not essential except so far as specified in the claims, and may be changed or modified without departing from the broader features 60 of the invention.

The invention having been described, what is claimed is:

1. A sole pressing machine, having, in combination, a pressing form, a supporting form, mechanism for relatively actuating the 65 forms to mold a sole between them, and a gage permanently located in a sole engaging position between the pressing surfaces of the two forms and having a sole engaging edge normally projecting above the upper surface 70 of the sole and contacting with the sole edge throughout substantially the entire thickness.

2. A sole pressing machine having, in combination, a supporting form, a co-operating pressing form, mechanism for relatively actuating the forms to mold a sole between them, and a resilient gage permanently located upon the surface of the supporting form and arranged to yield toward the face 80 of the supporting form when the two forms are moved into a pressing position.

3. A sole pressing machine having, in combination, a supporting form, a co-operating pressing form, mechanism for relatively 85 actuating the forms to mold a sole between them, and a gage located upon the surface of the supporting form and having a curved sole engaging edge arranged to flatten out 90 under pressure while maintaining a constant lateral position with relation to the forms.

4. A sole pressing machine, having, in combination, a supporting form, a co-operating pressing form, mechanism for relatively 95 actuating the forms to mold a sole between them, and a gage contacting with the supporting form at its opposite ends and arched in the direction of the length of the form to maintain the sole engaging edge in a constant lateral position when the gage member 100 yields under pressure.

5. A sole pressing machine comprising a form carrying slide, a form mounted upon the slide, a gage located upon the surface of the supporting form, and a gage supporting 105 arm fulcrumed upon the slide and having provision for angular adjustment to vary the lateral position of the gage and form.

HENRY W. EASTHAM.
